UNITED STATES PATENT OFFICE

2,181,354

CONDENSER FOR REFRIGERATORS

John Winters, New York, N. Y.

Application July 28, 1939, Serial No. 286,951

8 Claims. (Cl. 62—115)

This invention relates generally to air-cooled condensers used in condensing units of the compressor type for refrigeration systems, but more specifically to an air-cooled condenser construction embodying water-cooling means.

The present application embodies the inventions set forth in applicant's applications for patent, Serial Number 230,628, filed September 19, 1938, for Cooling means for refrigerator condensers, and Serial Number 230,629, filed September 19, 1938, for Condensers for refrigerators, both of which applications have been abandoned.

The main object of the invention resides in the provision of an air-cooled condenser of the above nature which embodies water-cooling means, the latter being put into operation when air-cooling alone is inadequate for refrigeration during the summer months or when the condenser is located in an environment of high temperature.

20 A further object of the invention resides in the provision of an air-cooled condenser having means for augmenting cooling by air and being capable of being connected in series with a conventional air-cooled condenser.

25 Another object of the invention resides in the provision of an air-cooled refrigerant condenser embodying water cooling means and which is simple to manufacture, efficient and economical in operation, and easily accessible for purposes of repair.

These objects and other incidental ends and advantages of the invention will hereinafter appear in the progress of the disclosure and as pointed out in the appended claims.

30 Accompanying this specification are drawings showing preferred forms of the invention wherein corresponding reference characters designate corresponding parts throughout the several views and wherein:

35 Figure 1 is a side view in elevation of a condenser unit including the specially constructed air-cooled condenser coil which is the subject matter of the invention herein.

Figure 2 is an end view in elevation of Figure 1.

Figure 3 is a fragmentary view in elevation partly in section showing a section of the condenser coil.

40 Figure 4 is a sectional view of Figure 3 along the plane 4—4 thereof.

Figure 5 is a diagrammatical view of a refrigeration system of the compressor type including the new condenser.

45 Figure 6 is a view similar to Figure 2 except that the condenser has the refrigerant passing

through the outer jacket and water passing through the inner tube.

Figure 7 is a view similar to Figure 5 except that the condenser has the refrigerant passing through the outer jacket and water passing 5 through the inner tube.

Figure 8 is a side view in elevation of a series arrangement of an air-cooled condenser coil embodying water cooling means, a conventional air-cooled condenser coil and a typical condenser 10 unit to which the said coils are secured.

Figure 9 is an end view in elevation of Figure 8.

Figure 10 is a fragmentary view in elevation foreshortened showing sections of the two condenser coils.

Figure 11 is a sectional view of Figure 10 along the plane 11—11 thereof.

Figure 12 is a diagrammatic view of a refrigeration system of the compressor type showing 20 the series arrangement of an air-cooled condenser coil embodying water cooling means and a conventional air-cooled condenser coil.

Figure 13 is an end view in elevation of a series arrangement of an air-cooled condenser coil embodying water cooling means and a conventional air-cooled condenser coil in conjunction with the typical condenser unit and is a modification of Figure 9 insofar as the outer jacket of the first mentioned coil has a refrigerant flowing therethrough instead of water.

Figure 14 is a diametrical view of a refrigeration system similar to the construction shown in Figure 12 except that the outer jacket of the air-cooled condenser embodying the water cooling 35 means has a refrigerant flowing therethrough instead of water.

It is well known that during the summer months, refrigeration is in greatest demand and that most trouble is encountered at this time of 40 the year with those systems operating on air-cooled condensers. Although the condenser unit of the system is stored at the coolest spot available, nevertheless the air surrounding the condenser may be so warm as to result in inadequate 45 cooling, thereby necessitating a greater load on the compressor in order to liquefy the refrigerant. Development of high pressure in a refrigeration system leads to greater cost of operation, danger of leakage of the refrigerant and increased wear 50 and tear on the compressor and movable elements of the system.

To overcome such inadequacy of air-cooled condensers, especially for the summer period, the applicant has provided an air-cooled con- 55

denser which embodies means for augmentation of cooling by water.

This new type of air-cooled condenser is adapted to form part of a typical commercial condensing unit for a compression refrigerating machine. Thus, in Figures 1 and 2, numeral 10 generally designates a conventional compressor having a flywheel 10', while numeral 11' indicates a fan secured to a motor 11, the said fan playing against the air-cooled condenser generally indicated by numeral 12. A typical refrigerant receiver 13 is also provided with the condensing unit as is a stand 14 to support all of the above mentioned parts. A belt 15 is adapted to connect the motor to flywheel 10' of compressor 10.

The diagrammatic view shown in Figure 5 represents the most desirable hook-up of a refrigeration system of the compressor type utilizing the new type of air cooled condenser. Numeral 16 represents a discharge line from compressor 10, the said line communicating with an inner pipe 17 of condenser 12, the said inner pipe 17 having an outer jacket 18 spaced therefrom by an annular spacing 19. The discharge line 16 passes through one end of the inner pipe 17 of condenser 12 and empties from the opposite end of the inner pipe 17 into receiver 13. From receiver 13 the refrigerant (in liquid condition) flows along line 20, the latter having a conventional drier 21 and a strainer 22 therealong. Line 20 terminates in an expansion valve and cooling or evaporating coil, the last mentioned valve and cooling coil not being shown in the drawings. The suction line of the system is indicated by numeral 23, the latter proceeding from the outlet end of the cooling coil. A conventional electric pressure control switch diagrammatically indicated by numeral 24 with a high pressure safety device and having a high pressure control line 25 and a low pressure control line 26 is connected across the two sides of compressor 10. An electric line 24' from the control switch 24 is adapted to limit excessive amount of compression. The high pressure control line 25 has a branch line 25' which is connected to a conventional high pressure water control valve diagrammatically represented by numeral 27, the latter cutting across the water line between the lower end of the condenser 12 and an inlet water valve 28. The corresponding outlet water valve 29 is at the upper end of condenser 12.

The high pressure water control valve 27 is of the diaphragm or bellows type which is acted upon by the condensing pressure. This valve opens a varying amount depending upon the condensing pressure and thus controls the supply of water. This type of valve is economical especially where the price of water is high.

It is to be observed that water inlet valve 28 and outlet water valve 29 are each provided with air vents 28' and 29' and water vents 28'' and 29'', so that the water within the annular space 19 of the double tube condenser may be drained off in the winter months to prevent freezing therein.

The system may be provided with a plurality of shut-off valves conveniently used for purposes of closing sections thereof, but as shown, two are indicated by numerals 30 and 31 secured to refrigerant receiver 13.

The water inlet valve 28 and the outlet valve 29 are positioned on the condenser 12 so that there will be a counterflow between the refrigerant passing along line 16, and into inner tube 17 downwardly and the cold water proceeding

from the inlet valve 28 on the bottom of condenser 12 and proceeding toward the top of the condenser. In this fashion it is possible to reduce the temperature of the condenser liquid or refrigerant to approximately the same temperature as the inlet water.

The air-cooled condenser comprising inner tubing 17 and spaced tubing 18 contains a plurality of end bends 36, the bends projecting from openings 35 in the side walls of the condenser framework 32. The framework 32 is mounted on a support 33 which is connected to stand 14 by means of webbing 34.

The condenser coil shown in Figures 3 and 4 is made by folding straight tube 17 within spaced 15 and straight tube 18, the tubes providing an annular space therebetween, so that water may run therethrough while a refrigerant proceeds through the inner tube. After the said tubes are coiled, preferably split fins 37 are inserted along 20 the outer tube between the bends 36.

Where the air is sufficiently cool so that a medium pressure is required to liquefy the refrigerant, the water valve 28 is rendered ineffective by means of the pressure controlled valve 27 25 thereby retaining the nature of condenser 12 as solely an air-cooled one.

One advantage of passing the refrigerant through the inner tube 17 of the double tube condenser 12 resides in the fact that should the 30 water in annular space 19 freeze, the resulting damage would only affect the outer tube 18 while the inner tube 17 containing the refrigerant would not be damaged since the pressure resulting from the expansion of the water upon 35 freezing would operate equally on all sides of inner tube 17.

However, the coupling between the condenser 12 and a water inlet and outlet may be varied as shown in Figures 6 and 7 so that the refrigerant passes through the outer jacket 18 of the condenser 12 and water flows through the inner tube 17. In this fashion, the refrigerant is air-cooled on the exterior and water cooled on the interior. Thus, the discharge line 16 45 containing the refrigerant passes through the upper end of the jacket 18 of condenser 12 by means of a coupling 38, the inner tube 17 containing water penetrating the coupling as at 17' and terminating in the outlet water valve 29. 50 The refrigerant empties at the opposite end of the condenser through jacket 18 into receiver 13 through coupling 39, the inner pipe 17 being in communication with high pressure water control valve 27.

From the standpoint of efficiency, the system where the refrigerant passes through the outer jacket of the condenser is superior to the system where the refrigerant passes through the inner tube.

The air-cooled condenser embodying water cooling means to be used when necessary as above described and shown in Figures 1-7 inclusive may be adapted to operate as a booster coil in a series arrangement with a conventional air-cooled coil, the latter being characterized as a pre-cooling coil. An arrangement of coils of the above nature is shown in Figures 8-14 inclusive, this arrangement being adapted to be used all year round whereby inadequate air-cooling and the ills consequent thereto are overcome. In such an arrangement of coils, the booster coil may adjust itself as an auxiliary air-cooled condenser when the surrounding air is at an adequately low temperature to render 70 75

liquefaction of the refrigerant at a low pressure. In the winter months, it is possible to convert both coils into a series of air-cooled condensers either manually or automatically as will herein-
5 after appear.

As in the case of the air-cooled coil embodying water cooling means, the series arrangement of booster and pre-cooling coils form part of a typical commercial condensing unit for a com-
10 pression refrigerating machine. Thus in Figures 8 and 9 numeral 10a generally designates a conventional compressor having a flywheel 10'a while numeral 11a indicates a motor with a fan 11'a attached thereto, the said fan playing against
15 the fins of both a conventional air-cooled or pre-cooling condenser generally indicated by numeral 12a and against the fins of an air-cooled condenser embodying means of water cooling or booster condenser generally designated by numeral 12'a, the said two condensers being disposed in parallelism one behind the other. A typical refrigerant receiver 13a is also provided with the condensing unit as is a stand 14a to support all of the above mentioned parts. A
20 belt 15a is adapted to connect the motor to flywheel 10'a of compressor 10a.

The diagrammatic view shown in Figure 12 represents the most desirable hook-up of a refrigeration system of the compressor type utilizing the series arrangement of a pre-cooling and a double tube booster condenser. In Figure 12, numeral 16a represents a discharge line from compressor 10a, the said line communicating with coiled tubing 17a of pre-cooling condenser 12a into the upper end of which line 16a carrying the refrigerant communicates. The refrigerant passes out of tubing 17a at the bottom of condenser 12a by a line 18a which extends to the inner tube 19a of the coiled double tube booster condenser 12'a, the spaced outer tube of said condenser being represented by numeral 20a. Between inner tube 19a and outer tube 20a, is an annular space 21a to accommodate a water flow. The refrigerant flows from the outer end of inner tube 19a into receiver 13a and then proceeds from the receiver (in liquid condition) along line 22a, the latter having a conventional drier 23a and strainer 24a therealong. Line 22a terminates in an expansion valve and cooling or evaporating coil, the valve and coil not being shown on the drawings. The suction line of the system is indicated by numeral 25a, the latter proceeding from the outlet end of the cooling coil. A conventional electric pressure control switch dia-
55 grammatically indicated by numeral 26a with a high pressure safety device and having a high pressure control line 27a and a low pressure control line 28a, is connected across the two sides of compressor 10a, an electric line 26'a from the control switch 26a being adapted to limit excessive amount of compression. The high pressure control line 27a has a branch line 27'a which is connected to a conventional high pressure water control valve diagrammatically represented by numeral 29a, the latter cutting across a water line 30a between the lower end of double tube condenser 12'a and an inlet water valve 31a. There is a shut-off water valve 32a on water line 30a near the lower end of double tube condenser 70 12'a directly before the point where line 30a communicates with outer tube 20a. An outlet water valve 33a is at the upper end of the double tube condenser 12'a.

The high pressure water control valve 29a is
75 of the diaphragm or bellows type, which is acted

upon by the condensing pressure. This valve opens a varying amount, depending upon the condensing pressure in line 27a and thus controls the supply of water coming from inlet valve 31a. This type of valve is economical, especially
5 where the price of water is high.

It is to be observed that water shut-off valve 32a and outlet water valve 33a are each provided with air vents 32'a and 33'a respectively and water vents 32''a and 33''a respectively, so that 10 the water within the annular space 21a of the double tube condenser 12'a may be drained off either in the winter months to prevent freezing therein or in the summer months when the re-
frigerant is adequately cooled by air.

15 The system may be provided with a plurality of shut-off valves conventionally used for purposes of closing sections thereof, but as shown, two are indicated by numerals 34a and 35a secured at opposite ends of refrigerant receiver 13a.

The water shut-off valve 32a is manually controlled. When opened, the amount of flow therethrough is controlled by the high pressure controlled water valve 29a, while the flow itself may be stopped by closing the water outlet valve 33a.
20 Shut-off valve 32a is positioned on the lower end of the double tube condenser 12'a so that there will be a counter flow between the refrigerant passing along line 18a and into inner tube 19a downwardly and the cooled water proceeding 30 from valve 32a on the bottom of condenser 12'a and proceeding toward the top thereof. In this fashion, it is possible to reduce the temperature of the condenser liquid or refrigerant to approximately the same temperature as the inlet 35 water.

Pre-cooling condenser 12a is provided with coiled tubing 17a wherein the end bends 36a project from openings 37a in the side walls of a condenser framework 38a. The double tube condenser 12'a having coiled inner tube 19a and coiled outer tube 20a similarly has a plurality of end bends 39a projecting from openings 40a in the side walls of a condenser framework 41a. Frameworks 38a and 41a are fixed in parallel 40 relationship and behind each other by means of webbing 42a which is connected to stand 14a. By this arrangement, single fan 11'a is able to play against both condensers through fins 43a of condenser 12'a and fins 44a of condenser 12'a.
45 Heat conducting fins 43a are distributed along the outer tube 20a of condenser 12'a, while fins 44a are distributed along tubing 17a of condenser 12a.

The double tubes of condenser 12'a shown in 55 Figures 10 and 11 are preferably made by folding straight tube 19a within spaced and straight tube 20a, the tubes providing an annular space 21a therebetween, so that water may run therethrough to cool a refrigerant proceeding through 60 the inner tube. Fins 43a are placed on tube 20a after the latter has been coiled.

Where the air is sufficiently cool so that a medium pressure is required to liquefy the refrigerant, the flow of water from the inlet water 65 valve 31a is stopped by means of the pressure controlled valve 29a, thereby rendering it unnecessary to close shut-off valve 32a manually. When this occurs, booster condenser 12'a operates as a purely air-cooled condenser in con-
70 junction with the pre-cooling air-cooled condenser 12a and thereby brings about more cooling than a single conventional air-cooled condenser.

The advantage of passing the refrigerant 75

- through inner tube 19a of the double tube condenser 12'a resides in the fact that should the water in annular space 21a freeze, the resulting damage would affect the outer tube 20a, while 5 the inner tube 19a containing the refrigerant would not be damaged since the pressure resulting from the expansion of the water upon freezing would operate equally on all sides of inner tube 19a.
- 10 Figures 13 and 14 show the same series arrangement of the two condensers shown in Figures 9 and 12 except that the booster condenser 12'a has a refrigerant flowing through the outer jacket 20a instead of the inner tube 19a. For 15 such purpose, the ends of the condenser 12'a are connected to two couplings, an upper coupling 44'a and a lower coupling 45a. Coupling 44'a connects the refrigerant line 18a to the upper end 20 of jacket 20a, the inner tube 19a passing through the coupling 44'a as at 19'a and terminating in 25 the outlet water valve 33a. The refrigerant empties at the opposite end of the condenser 12'a from jacket 20a into receiver 13a through the lower coupling 45a, the inner tube 19a containing water being in communication with the high pressure water control valve 29a.

From the standpoint of efficiency this system of cooling is superior to that system wherein the refrigerant proceeds through the inner tube and 30 the water through the outer jacket.

The air-cooled condensers embodying water cooling means as well as the single tube condenser herein described may be made from any metal which is resistant to the action of the refrigerant.

I wish it understood that minor changes and variations in the shape, connection, arrangement, location, material and integration of parts, may all be resorted to without departing from the 40 spirit of the invention and without departing from the scope of the appended claims.

I claim:

1. A refrigeration system including a compressor and a condenser coil including air cooling means normally adapted to condense sufficient refrigerant for a fixed capacity of said compressor, auxiliary cooling means other than air cooling to augment condensation of the refrigerant to compensate for variations in load, said auxiliary cooling means being embodied in said coil and being operable during periods when air cooling is inadequate for refrigeration.

2. A refrigeration system including a compressor and a condenser coil including air cooling means normally adapted to condense sufficient refrigerant for a fixed capacity of said compressor, auxiliary cooling means other than air cooling to augment condensation of the refrigerant to compensate for variations in load, said auxil-

iary cooling means being embodied in said coil, being operable during periods when air cooling is inadequate for refrigeration and including an inner coil, a water inlet valve and a water outlet valve attached to the ends of one of said coils. 5

3. A refrigeration system including a compressor and a condenser coil including air cooling means normally adapted to condense sufficient refrigerant for a fixed capacity of said compressor, auxiliary cooling means to augment condensation of the refrigerant to compensate for variations in load, said auxiliary cooling means including an inner coil providing a conduit for water and being operable during periods when air cooling is inadequate for refrigeration, the 10 refrigerant passing between the inner and condenser coils.

4. A refrigeration system including a compressor and a condenser coil including air cooling means normally adapted to condense sufficient 20 refrigerant for a fixed capacity of said compressor, auxiliary cooling means to augment condensation of the refrigerant to compensate for variations in load, said auxiliary cooling means including an inner coil providing a conduit for 25 the refrigerant, the outer coil serving as a conduit for water and being operable during periods when air cooling is inadequate for refrigeration.

5. A refrigeration system as set forth in claim 3 wherein the inner coil is provided with a water 30 inlet and a water outlet valve at the ends thereof.

6. A refrigeration system as set forth in claim 4 wherein the outer coil is provided with a water inlet and a water outlet valve at the ends thereof.

7. A refrigeration system including a compressor and a condenser coil including air cooling means normally adapted to condense sufficient refrigerant for a fixed capacity of said compressor, auxiliary cooling means other than air cooling to augment condensation of the refrigerant 40 to compensate for variations in load, said auxiliary cooling means being embodied in said coil and being operable during periods when air cooling is inadequate for refrigeration, another condenser coil having air cooling means and being 45 connected to the first mentioned condenser coil to precool the refrigerant before passing into said first mentioned condenser.

8. In the operation of a refrigeration system including a compressor and a condenser coil including air cooling means normally adapted to condense sufficient refrigerant for a fixed capacity of said compressor, the step of internally cooling the condenser coil to augment condensation of the refrigerant to compensate for variations in load during periods when air cooling is 50 inadequate for refrigeration.

JOHN WINTERS.
